Specification for Design.

Patented Nov. 22, 1921.

Application filed July 15, 1921. Serial No. 485,113. Term of patent 14 years.

To all whom it may concern:

Be it known that I, EDMOND C. HOWARD, a citizen of the United States, residing at Norfolk, in the county of Norfolk and State of Virginia, have invented a new, original, and ornamental Design for Sound-Conduits for Phonographs, of which the following is a specification, reference being had to the accompanying drawing, forming part thereof.

Figure 1 is a side view of a sound conduit for phonographs, showing my new design, and;

Fig. 2 is a plan view of a sound conduit for phonographs, showing my new design.

I claim:

The ornamental design for a sound conduit for phonographs, as shown.

E. C. HOWARD.
